UNITED STATES PATENT OFFICE.

CLAYTON AUBRA DUNHAM, OF MARSHALLTOWN, IOWA.

FEED-WATER REGULATOR.

No. 884,913.

Specification of Letters Patent.

Patented April 14, 1908.

Application filed January 30, 1907. Serial No. 354,824.

To all whom it may concern:

Be it known that I, CLAYTON AUBRA DUNHAM, a citizen of the United States, and a resident of Marshalltown, in the county of 5 Marshall and State of Iowa, have invented a new and Improved Feed-Water Regulator, of which the following is a full, clear, and exact description.

This invention relates to certain improvements in vacuum vapor or pressure heating systems, and more particularly to improvements in the system disclosed and claimed in my United States Patent No. 816,972, granted April 3, 1906.

15 The object of the invention is to provide an improved means for automatically regulating and controlling the pump which returns the water of condensation from the radiators to the boiler, whereby the pump 20 will be automatically started in operation upon the accumulation of a predetermined quantity of water in the receiver and the operation of the pump interrupted when the water falls below said predetermined limit.

25 The invention consists in certain features of construction and combination of parts, all of which will be fully set forth hereinafter and particularly pointed out in the claims.

Reference is to be had to the accompanying 30 drawings forming a part of this specification, in which similar characters of reference indicate corresponding parts in both the figures, in which

Figure 1 is a side elevation of one embodiment of my improved system; and Fig. 2 is a vertical longitudinal section through the automatic air relief and pump governor.

In connection with my improved system I employ a boiler 10 of any suitable type 40 adapted for the generation of steam, and connected to this boiler is the main steam delivery pipe 11.

In the form of my invention illustrated in the accompanying drawings, the delivery 45 main 11 leads through the separator 12 to any suitable form of steam engine 13 controlled by a throttle valve 14, said separator serving to remove any water of condensation which may be present in the steam and prevent 50 said water from entering the engine. This engine may be employed for any suitable purpose desired, and the exhaust steam from said engine employed for heating purposes. The said exhaust steam is conducted 55 through a conduit 15 to a feed-water heater 16 of any suitable character, and delivered

from said feed-water heater through a conduit 17. This conduit is connected to the heating main 18 and also to the vent pipe 19 leading to the roof of the building. The 60 heating main is provided with valves 20 of any suitable character and preferably the said main is inclined downward from the point at which the branch pipe 21 leading from the conduit 17 enters. Any water of 65 condensation in the pipe 18 may be drawn off at the ends of said pipe through an automatic steam trap 22.

The heating main 18 is connected to the radiators 23 by branch conduits 24 controlled 70 by any suitable form of valves 25, and the water of condensation and air within said radiators are permitted to escape through automatic thermostatic traps 26 to the return pipes 27. These latter deliver through a 75 common return pipe 28 to the receiver 29, and from this receiver the liquid is pumped through the feed-water heater and back to the boiler. The vent pipe 19 is provided with a back pressure valve 30, and the conduit 17 leading steam from the feed-water heater is connected to the steam main 11 by a branch conduit 31, including a pressure reducing valve 32, whereby if the engine is stopped or if the pressure within the radiators becomes reduced below a predetermined 80 limit, fresh steam may pass directly from the steam main 11 to the heating main 18 until the said pressure has been restored.

The specific form of automatic air relief 90 and pump governor which I preferably employ, is illustrated more in detail in Fig. 2, and preferably comprises a cylindrical body portion having the inlet conduit 28 connected thereto at a point adjacent the upper end, 95 and having a delivery conduit 33 leading from a point adjacent the lower end and delivering to the water cylinder of a steam pump 34. The receiver 29 is provided with a false bottom 35 which may, if desired, be 100 integral with the walls of the receiver, and directly below this false bottom 35 is a second or outer bottom 36. These two bottoms are spaced apart to form a chamber 37 therebetween which chamber communicates with 105 the atmosphere by means of a centrally-disposed tube 38 passing through the false bottom 35 and through the top 39 of the receiver. The space between the two bottoms 35 and 36 is sub-divided by an imperforate flexible 110 diaphragm 40 having its edges rigidly secured between the two bottoms. The space

beneath the diaphragm communicates with the interior of the receiver by means of a conduit 41, and the said chamber is provided with a draw-off valve 42, whereby the chamber and receiver may be drained.

Within the conduit 41 is located a valve 57 whereby the passage of the liquid may be readily controlled to hold the valve 45, hereinafter described, in its open or closed position; and the top 39 is provided with any suitable form of air escape means, as for instance a pipe 55, having a check valve 56 whereby the fluctuations in the level of the water in the receiver serve to force the air out of the system.

The steam pump 34 is of any suitable construction and adapted to be operated by steam delivered thereto through a conduit 44 leading from the steam main 11. Within 20 this conduit is interposed a valve 45 connected to and operated by the diaphragm 40 above referred to. The valve 45 is preferably located within a valve casing 46 supported upon the receiver 29, and the valve 25 stem 47 leads through a packing box 48 to a point directly above the centrally-disposed tube 38. The valve stem is here connected to a rod 49 leading through said tube and connected directly to the diaphragm 40. At 30 the point of connection between the valve stem 47 and the rod 49, there is interposed a yoke through which passes a lever arm 50 pivotally connected to a bracket 51 which supports the valve casing, and upon the outer 35 end of this lever is provided a weight 52 of any suitable character.

The tube 38 is open directly to the atmosphere, and as no liquid can reach the upper side of the diaphragm 40, the latter is at all 40 times subjected to atmospheric pressure. The lower side of the diaphragm 40 is directly exposed to the pressure of the liquid within the receiver 29 except when valve 57 is closed, and as liquid accumulates in said receiver, 45 the pressure increases and tends to lift the diaphragm 40 in opposition to the action of the weight 52. As the diaphragm rises the motion is imparted directly to the valve 45, and as this valve opens, the small steam 50 pump 34 is started in operation and withdraws the water of condensation from the receiver 29 and delivers it through a conduit 53 to the feed-water heater 16, from which it may pass to the boiler through a suitable conduit 54.

In the operation of my improved heating system, steam is employed for heating the water of condensation before said water is returned to the boiler and the steam is then delivered under a constant but rather low pressure to the heating main 18. This main connects directly with supply pipes leading to all of the radiators, the delivery of steam to said radiators being readily controlled by the 60 valves 25. As soon as the steam condenses 65

within the radiators and the water of condensation reaches the thermostatic valves 26, it may readily flow from the radiators to the return pipes 27, but as soon as the air and the water of condensation have all left the radiators the thermostatic valves 26 automatically close and prevent the escape of steam. The return pipes 27 all deliver to the pipe 28 leading to the receiver 29, from which receiver the water is pumped through the feed-water heater to the boiler and the air escapes through vent pipe 55 and check valve 56 to the atmosphere. In starting the system the weight 52 is raised, by hand, thus raising the diaphragm and drawing air through the passage 41 to the space beneath the diaphragm. The valve is then closed and the escape of the air prevented, whereby the diaphragm is held in its raised position and the valve 45, which is rigidly connected to the diaphragm, is held in its open position. Steam may thus pass the valve 45 and operate the pump which is allowed to run until the air is sucked out of the system, the pump being allowed to discharge to the atmosphere rather than into the boiler as in the normal operation. The valve 57 is then opened and steam is turned into the heating system, after which the operation continues automatically. Upon the accumulation of water within the receiver 90 95 100 105 110 115 120 125 130 135 140 145 150 155 160 165 170 175 180 185 190 195 200 205 210 215 220 225 230 235 240 245 250 255 260 265 270 275 phragm to the outside atmosphere, a conduit leading from said chamber at the other side of the diaphragm and communicating with the interior of the receiver, and means operatively connected to said diaphragm for controlling the withdrawal of fluid from said receiver.

3. A device of the class described, comprising a receiver having an inlet and an outlet and having an inner and an outer bottom forming a chamber therebetween, a diaphragm within said chamber, a conduit leading from said chamber at one side of the diaphragm to the outside atmosphere, a conduit leading from said chamber at the other side of the diaphragm and communicating with the interior of the receiver, means for controlling said last mentioned conduit, and means operatively connected to said diaphragm for controlling the withdrawal of fluid from said receiver.

4. A device of the class described, comprising a receiver having a partition wall subdividing the receiver into two chambers, an inlet and an outlet for one of said chambers, a diaphragm within the other chamber and having one surface exposed to atmospheric pressure, a conduit leading from the first mentioned chamber to the last mentioned chamber at the other side of the diaphragm, a valve controlled by the movement of said diaphragm, and means for controlling said conduit.

5. A controller for feed pumps, comprising a receiver through which the liquid flows to the inlet of the pump a conduit for supplying a motive fluid for operating said pump, a valve in said conduit, a diaphragm within said receiver and having one surface thereof exposed to the fluid within the receiver and the other surface exposed to atmospheric pressure, means connecting said diaphragm to said valve for operating the latter, and means for shutting off communication between said receiver and the surface of said diaphragm.

6. A heating system, comprising a receiver for the water of condensation, a pump connected to said receiver and adapted to return the water of condensation to the boiler, said receiver having inner and outer bottoms

forming a chamber therebetween, a diaphragm within said chamber, a conduit leading from the chamber at a point above the diaphragm to the outside atmosphere, a conduit connecting the chamber below the diaphragm to the interior of the receiver, and means connected to said diaphragm and extending through said first mentioned conduit for automatically controlling the operation of the pump.

7. A heating system, comprising a receiver for the water of condensation, a pump having its suction chamber connected to said receiver and adapted to return the water of condensation to the boiler, a motor for operating said pump, a conduit adapted to deliver a motive fluid to said motor, a valve casing in said conduit and supported upon said receiver, a valve within said valve casing, said receiver being provided with an inner and an outer bottom forming a chamber therebetween, an imperforate diaphragm within said chamber, a conduit connecting the chamber below the diaphragm with the outside atmosphere, and a rod connecting said diaphragm and said valve, whereby the operation of the pump may be automatically controlled according to the quantity of water of condensation in the receiver.

8. A device of the class described, comprising a receiver having a transverse partition subdividing it into two compartments, an inlet and an outlet for the upper compartment, a tube extending through the upper compartment and communicating with the lower compartment, a diaphragm in the lower compartment, a conduit connecting the upper compartment with the lower compartment below the diaphragm, a conduit, a valve for controlling said last-mentioned conduit, and means extending through said tube and operatively connecting said diaphragm and said valve.

In testimony whereof I have signed my name to this specification in the presence of two subscribing witnesses.

CLAYTON AUBRA DUNHAM.
